UNITED STATES PATENT OFFICE.

ROBERT J. MONTGOMERY, OF CHICAGO, ILLINOIS.

AUTOMOBILE WASHING-BRUSH.

1,133,390.

Specification of Letters Patent. Patented Mar. 30, 1915.

Application filed August 6, 1913. Serial No. 733,309.

To all whom it may concern:

Be it known that I, ROBERT J. MONTGOMERY, a citizen of the United States, residing at Chicago, in the county of Cook and State of Illinois, have invented certain new and useful Improvements in Automobile Washing-Brushes, of which the following is a specification.

My invention relates to brushes, and particularly to brushes equipped with means for discharging water upon the object operated upon by the brush, such brushes being especially adapted for use in washing automobiles, carriages, etc.

The object of my invention is to provide such a brush in which the brush member will be removable; to provide improved means for receiving and supporting the brush in operative position; to provide improved locking means for securing it in position; and to provide an improved water supply connection for supporting the brush and discharging water therethrough. I accomplish these objects as hereinafter described and as illustrated in the drawings.

What I regard as new is set forth in the claims.

In the accompanying drawings,—Figure 1 is a side view of my improved device, showing the brush in position, the brush being partly broken away to show the outer end of the brush support; Fig. 2 is a view illustrating the wire or equivalent flexible member which carries the bristles and by which the brush is secured to the support; Fig. 3 is a vertical section of the brush supporting device, which also forms the water connection through which water is supplied to it; Fig. 4 is a detail, illustrating the outer end of the support; and Fig. 5 is a plan view of the locking collar.

Referring to the drawings,—6 indicates the brush, which in the construction shown, comprises a central flexible support 7, which is practically a twisted wire, but may be made of any other suitable material. The wire 7 is bent into a kite shape, as shown in Fig. 2, its ends, however, being straight and parallel with each other, as shown at 8 in said figure. Near its ends the wire is provided with opposing notches 9 on its inner face, which are used in locking the brush in position, as will be hereinafter described.

The brush support and water connection comprises a tube 10, which is provided at one end with a screw coupling 11, by which

it may be attached to a hose, or other source of water supply.

12 indicates a hand-piece in the form of a sleeve fitted upon the tube 10, as shown in Fig. 3. At its opposite end the tube 10 carries a cap 13, which is secured thereupon and is provided with two opposite perforations 14, shown in Fig. 3.

15 indicates a U-shaped clip which is mounted upon the cap 13 by a pivot 16, so that it may be rotated either to close the openings 14 or to expose them. A further function of the clip 15 is to embrace the central portion of the wire 7, as shown in Fig. 1, to hold the intermediate portion of the brush against lateral movement.

17 indicates sleeves secured at opposite sides of the tube 10 at about the longitudinal center thereof, said sleeves being adapted to receive the straight ends 8 of the wire 7. Between the sleeves 17 and the outer end of the tube, a number of perforations 18 are provided for discharging water laterally from the tube.

19 indicates a locking member in the form of a collar, which is fitted upon the tube 10, between the handle 12 and the sleeves 17. As best shown in Figs. 1 and 3, the collar 19 is provided with a knurled flange 20 at its lower margin and with oppositely-disposed laterally-projecting lugs 21 at its upper margin, said lugs being adapted to engage the notches 9 in the wire 8 when the wire is in position in the sleeves 17. At their lower ends said sleeves 17 are cut away, as shown at 22 in Fig. 3, to permit the lugs 21 to move into engagement with the notches 9 when the collar 19 is rotated for that purpose. The locking collar 19 is free to move longitudinally upon the tube 10, so that when not in engagement with the wire 8, it may be dropped down out of the way.

When the parts are assembled, the straight ends of the wire 7 lie in the sleeves 17 with the notches 9 opposite the cut away portions 22 of said sleeves. The locking collar 19 is then in the position shown in Figs. 1 and 3, its lugs 21 being in engagement with the notches 9. The lugs 21 project far enough so that when in operative position they press the ends of the wire 8 out against the sleeves 17, thereby securing a clamping effect which prevents accidental displacement of the collar with the ends of the wire. The clip 15 straddles the wire and holds the intermediate portion of the brush against

lateral displacement, but when the water is turned on it is discharged in jets through the lateral openings 18 and through the end portions 14. When it is desired to remove 5 the brush, the collar 19 is partly rotated, thereby releasing the wire 7 and permitting the brush to be removed.

The tube 10 may be used without the brush if desired, and if in such case it is 10 not desired to discharge water through the end openings 14, they may be closed by rotating the clip 15 to a position where it overlies said openings.

That which I claim as my invention, and 15 desire to secure by Letters Patent, is,—

1. A device of the character described, comprising in combination, a tube having water discharging openings through its wall and having a coupling at one end, a cap at 20 the other end of the tube, said cap having an opening therethrough, a clip pivotally mounted on the cap and adapted to be adjusted to cover the opening in the cap, a brush-supporting member held in place at 25 its central portion by said pivoted clip, and other means carried by the tube for holding in place the end portions of said brush-supporting member.

2. A device of the character described, 30 comprising a tube, a coupling at one end thereof, a cap at the other end of said tube, lateral perforations in the latter portion of said tube, sleeves mounted intermediately upon said tube, a brush-supporting member 35 having projecting ends adapted to fit into

said sleeves, a brush carried by said brush-supporting member, and movable means for locking the ends of said brush-supporting member in said sleeves.

3. A device of the character described, 4 comprising a tube, a coupling at one end thereof, a cap at the other end of said tube, lateral perforations in the latter portion of said tube, sleeves mounted intermediately upon said tube, a brush-supporting member having projecting ends adapted to fit into said sleeves, a brush carried by said brush-supporting member, and a clip carried by said cap and adapted to engage said brush-supporting member intermediately.

4. A device of the character described, comprising a tube, a coupling at one end thereof, a cap at the other end of said tube, lateral perforations in the latter portion of said tube, sleeves mounted intermediately upon said tube, a brush-supporting member having projecting ends adapted to fit into said sleeves, a brush carried by said brush-supporting member, and a collar mounted on said tube and movable longitudinally thereof, said collar having laterally projecting portions adapted to engage notches in the end portions of the brush-supporting member when the latter are in position in said sleeves.

ROBERT J. MONTGOMERY.
